UNITED STATES PATENT OFFICE.

ALBERT G. HRON, OF KEWASKUM, WISCONSIN, ASSIGNOR TO KEWASKUM ALUMINUM CO., OF KEWASKUM, WISCONSIN.

PERCOLATOR.

Application filed March 22, 1929. Serial No. 349,144.

This invention pertains to percolators, and more particularly to that type commonly known as cold water percolators, in which the receptacle is provided with a heating base having a well formed therein for 5 operation with the conventional fountain.

The primary object of the present invention resides in the provision of a novel and inexpensive structure of base and assembly 10 with the receptacle, whereby an extremely rigid and secure joint is obtained, which avoids possibility of leakage or loosening of the base from the receptacle.

Incidental to the foregoing, a more specific object resides in the provision of a cast base having an integral portion beaded over with a portion of the receptacle to form the attaching joint.

A still further object is to provide a cast 20 aluminum base with an integral sleeve of pliable metal, adapted to project through the bottom of the receptacle and to be crimped over a portion of the receptacle on the interior of the same, thus rigidly clamping 25 the receptacle to the base.

With the above and other objects in view, which will appear as the description proceeds, the invention resides in the novel construction combination and arrangement of 30 parts substantially as hereinafter described and more particularly defined by the appended claims, it being understood that such changes in the precise embodiment of the herein disclosed invention may 35 be made as come within the scope of the claims.

In the accompanying drawing is illustrated one complete example of the physical embodiment of the present invention 40 constructed according to the best mode so far devised for the practical application of the principles thereof.

In the drawing, Figure 1 is a vertical section through a portion of a percolator constructed in accordance with the present invention, and

Figure 2 is a detail section of the same prior to crimping the receptacle to the base.

Referring now more particularly to the 50 accompanying drawing, the numeral 1 designates a portion of a conventional percolator receptacle, which it is understood is provided with the usual spout and handle, not shown. The bottom of the receptacle 1 55 is provided with a central annular opening

2, surrounding which is an inturned bead 3 formed by crimping the material over in a manner hereinafter described. Associated with the bottom of the receptacle is a cast base 4 provided with the usual central well 5, which cooperates with the fountain to cause the contents of the receptacle to percolate through the material contained in the usual reservoir, not shown. The top of the base 4 is provided with a flattened surface 6, which engages the bottom of the receptacle adjacent the central opening 2.

In the present instance, in which the base 4 is cast from aluminum, a cylindrical sleeve 7 is provided for the well, the same being 70 cast integrally with the base to form a secure connection. The upper end of the sleeve 7 projects through the central opening 2 and is crimped over the internal bead 3 formed in the receptacle and thus cooperates with the flat upper surface 6 to rigidly and securely clamp the receptacle to the base.

As best shown in Figure 2, the present structure lends itself to an inexpensive operation of assembling, in that prior to the crimping operation, the receptacle is merely assembled upon the base with the sleeve 6 projecting through the central opening and surrounded by an upturned portion of the 85 receptacle. Thus, in the crimping operation, both the sleeve and a portion of the receptacle are turned over simultaneously, which not only permits the sleeve and receptacle to be securely clamped together, but 90 also eliminates a separate operation in forming the bead 2.

From the foregoing explanation it will be obvious that an exceedingly simple and effective joint has been provided between the 95 base and receptacle, which eliminates possibility of leakage or of the receptacle becoming loosened.

It is further pointed out that the particular advantage of providing a cast aluminum base with an integral sleeve insert of pliable metal, materially facilitates the crimping operation, in that it is well known that cast aluminum is not as adaptable to crimping or beading as other well known materials. 100 Therefore, some objection would be encountered should the extension of the base, projecting through the receptacle and crimped thereover, be formed of the same cast material as the base. However, it will be un- 110

derstood that although the present form is considered preferable, that the invention also contemplates a structure in which the projection of the base may be cast integral 5 with the same instead of comprising a separate sleeve moulded into the base during the casting operation.

As previously explained, the well 5, formed in the base, cooperates with the 10 fountain in the conventional manner. The fountain illustrated comprises the usual fountain tube 8 which communicates with the valve chamber 9, which is provided with a cylindrical sleeve 10 removably mounted 15 within the well 7. In the present instance, the fountain is shown supported by engagement of the sleeve 10 with the bottom of the well. However, it will be appreciated that the length of the sleeve may be materially 20 reduced, and any means provided for supporting the same on the inturned bead of the sleeve 7.

Although the fountain has been described in some detail, no novelty is embodied in 25 the same, nor does it constitute any part of the present invention other than in the broad combination.

I claim:

1. A percolator comprising a receptacle 30 provided with a central opening in its bottom, a base, and an integral extension carried by said base and crimped over the edge of said central opening to form a tight joint between the receptacle and base.

2. A percolator comprising a receptacle 35 provided with a central opening in its bottom, a base provided with a well in alignment with said central opening, and an integral extension carried by said base and 40 projecting through said opening and crimped over the edge of the same to form a tight joint between the receptacle and base.

3. A percolator comprising a receptacle 45 provided with a central opening in its bottom and an internal bead surrounding said opening, a base provided with a well in alignment with said central opening, and an integral extension carried by said base and crimped over the internal bead of the 50 receptacle to form a tight joint between the receptacle and base.

4. A percolator comprising a receptacle 55 provided with a central opening in its bottom and an internal bead surrounding said opening, a base provided with a well in alignment with said central opening, a sleeve secured in said well and projecting through

said central opening and crimped over said internal bead to form a tight joint between the receptacle and base. 60

5. A percolator comprising a receptacle provided with a central opening in its bottom, a base provided with a well in alignment with said central opening, and a cylindrical sleeve secured in said well and projecting through said central opening and crimped over the edge of the same to securely clamp said receptacle to said base. 65

6. A percolator comprising a receptacle provided with a central opening in its bottom, a base provided with a well in alignment with said central opening, said base having a flat upper face engaging the bottom of said receptacle, and an integral extension carried by said base and projecting through said central opening and crimped over the edge of the same to clamp said receptacle upon the flat upper face of said base. 70

7. A percolator comprising a receptacle provided with a central opening, a cast 80 aluminum base provided with a well in alignment with said opening, a pliable metal sleeve secured in said well and projecting through said central opening and crimped over the edge of the same to clamp said receptacle to said base. 85

8. A percolator comprising a receptacle provided with a central opening in its bottom, a cast aluminum base having a well in alignment with said central opening, and a 90 pliable metal sleeve cast in the well of said base and projecting through said central opening and crimped over the edge thereof to securely clamp the receptacle to the base. 95

9. In a percolator comprising a receptacle provided with a central opening in its bottom surrounded by an inturned bead, a cast aluminum base provided with a well in alignment with said central opening, said base being provided with a flat upper face engaging the bottom of said receptacle, and a pliable metal sleeve cast integral with said well and projecting through said well and projecting through said central opening and crimped over the internal bead surrounding the same to securely clamp the receptacle to the flat upper face of the base. 100

In testimony that I claim the foregoing I have hereunto set my hand at Kewaskum, 110 in the county of Washington and State of Wisconsin.

ALBERT G. HRON.
